UNITED STATES PATENT OFFICE

HENRY W. KRAMER, OF KINGSTON, NEW YORK, ASSIGNOR TO RALPH P. YOUNG, OF MARLBORO, NEW YORK

HANDLE FOR WOODEN BASKETS

Application filed May 14, 1926. Serial No. 109,029.

My invention consists in the novel features hereinafter described, reference being had to the accompanying drawing which illustrates several embodiments of the same selected by me for purposes of illustration, and the said invention is fully disclosed in the following description and claims.

The object of my invention is to provide a metallic handle for wooden baskets of the type ordinarily used for holding grapes and other fruit, vegetables, etc. These baskets are ordinarily composed of a wooden bottom, around the edges of which are secured sides of wood veneer which are bound around the bottom on the outside, and around the upper edge usually both inside and outside, with narrow binding strips of wood veneer secured in place by tacks, or small nails, or staples. My present invention has for its object the provision of a metallic handle comprising a bail member, and separately formed attaching members which can be secured to the sides of the basket preferably at the factory where the basket is made, and which are constructed to engage the basket at two opposite points adjacent to its upper edge, the bail member and said attaching members being provided with interengaging portions, to permit the bail member to be attached to the attaching members at the point where the baskets are packed, and the attaching members being so constructed as not to interfere with the nesting of the baskets at the factory for shipment. The handle is also provided with means for holding the cover on the basket against vertical or longitudinal movement. My invention also contemplates means for anchoring the attaching members of the handle to the bottom of the basket to relieve the sides and the nails which attach the sides to the bottom from strain.

In the accompanying drawing,

Fig. 1, represents a perspective view partly in section showing a wooden basket provided with a metallic handle embodying my invention.

Fig. 2, is a detail view of the bail member of the handle.

Fig. 3, is an enlarged detail view of one

of the attaching members shown in elevation, and the adjacent portions of the basket and cover being shown in section.

Fig. 4, is a similar view showing a slightly modified form of attaching member.

Figs. 5 and 6, are views similar to Fig. 3, showing further modified forms of the attaching member.

Fig. 7, is a detail view of the attaching member shown in Fig. 6, looking toward the outside of the basket.

Figs. 8 and 9, are detail views showing slightly modified forms of the bail member.

Fig. 10, is a view partly in section showing a portion of a basket with my improved handle attached, and one of the anchoring members for connecting the attaching members to the bottom of the basket.

Fig. 11, is a detail perspective view of one of the anchoring devices.

Fig. 12, is a similar view showing a slightly modified form of anchoring device.

Fig. 13, is a sectional view of a basket showing one form of my improved handle applied thereto, in connection with an anchoring device for the attaching members extending entirely around the bottom and sides of the basket.

Fig. 14, represents a view similar to Fig. 10, showing another modified form of anchoring device.

Fig. 15, is a detailed sectional view of a basket showing the form of attaching device illustrated in Fig. 5, coupled with the anchoring member of Fig. 11.

In Fig. 1, A, represents the bottom of the basket, B, the veneer pieces forming the sides, C, the bottom binding strip, D, the exterior top binding strip, D¹, the interior top binding strip, E, the cover which may be in one piece if desired, but which is usually formed of longitudinal strips, e, a centrally located transverse cleat, e¹, and additional transverse cleats, one of which is indicated at e². This is the usual construction of this type of basket at the present time.

My improved handle comprises the bail member having a hand engaging portion, 1, which is preferably provided centrally with means for engaging a hook on a ladder, or

other support for the purpose of holding the basket in a horizontal position while it is being filled, and preventing the spilling of the fruit or other contents during the packing of the basket. As shown in Figs. 1 and 2, the hand engaging portion, 1, is provided with a simple loop indicated at 2, which will not interfere with the carrying of the basket by hand, and at the same time will afford a centrally located device for engaging a hook and preventing the hook from sliding in either direction from the central position, which would result in tilting the basket and perhaps spilling the contents. The bail member is also provided with depending arms, 3, 3, each of which is provided with a locking portion, indicated at 4, which in this instance is located at the lower end of each arm and is in the form of an open loop horizontally disposed, and each of the arms, 3, is also provided, in this instance, above the locking device, 4, with a guiding device, 5, which in this instance is in the form of a closed loop horizontally disposed. In Fig. 1, I have shown the basket provided with two attaching members forming part of the handle, said attaching members being formed separately from the bail member and constructed to be attached to the upper part of the basket at opposite sides, centrally thereof. Each of the said attaching members is provided with means for securing it to the basket, and also with a guiding portion to engage the guiding portion of a bail arm, and also with a locking portion to engage the locking portion of a bail arm. As shown in Figs. 1 and 3, each of the attaching members is formed of wire, as is the bail member, and comprises a vertical portion, 6, adapted to engage the exterior binding strip, D, (or the exterior of the basket side if no binding strip is provided thereon). At its lower end, this part, 6, is provided with an inwardly extending portion, 7, an upwardly extending portion, 8, parallel to the portion, 6, and spaced from it by the part, 7, a distance substantially equal to the material of the basket side to be embraced between them and terminating in a horizontal attaching point, 9, bent outwardly toward the exterior of the basket. When these parts are formed, they will preferably be in the position indicated in dotted lines in Fig. 3, that is to say, with the part, 8, disposed angularly to the part, 6, and the portion 9, being either in substantial prolongation of the part, 8, or bent at a slight angle thereto so as to permit the parts, 8 and 9, to be inserted through a hole indicated at b, in the basket side, B, preferably just below the lower edges of the binding strips, D and D¹, after which the point, 9, will be bent into a horizontal position, and the part, 8, will be bent in a direction toward the exterior portion, 6, so as to force the point, 9, through the binding strips, D and D¹, and through the side, B, as indicated in full lines in Fig. 3, thus securing the attaching member rigidly to the basket side adjacent to its upper edge. The exterior portion, 6, of the attaching member extends above the top edge of the basket, and is provided with a downwardly bent portion, 10, and an upwardly and outwardly projecting arm, 11, forming at their junction a retaining shoulder, indicated at 12, and providing a locking loop indicated at 13, at the junction between the portion, 6, and the portion, 10. The upper end of the upwardly extending arm, 11, is provided with a guiding portion indicated at 14, which may be bent slightly out of alignment with the arm, 11, as shown in Fig. 3, if desired, to enable it to engage the guiding loop, 5, on one of the bail arms, 3. It will be seen that the attaching members can be applied to the baskets at the factory at the time the baskets are made, and that they will not interfere with the nesting of the baskets for shipment. It is found convenient to nest them in any desired numbers, as say, 25 to a nest, and while the entire handle can be applied at the point where the basket is packed, it is preferable to attach the attaching members to the basket at the factory, and to ship the bail members for each nest of baskets with the nest, which can be readily done by placing them in the topmost basket, or otherwise securing them to the package. To apply the bail member to the basket when it is desired to pack it, it is only necessary to place the guiding loops, 5, of each bail arm in engagement with one of the guiding portions, 14, of the attaching members, and force the bail arm downward at the same time springing the locking hooks, 4, of the bail member into engagement with the locking loops, 13, of the attaching members. The parts are so constructed, that, the locking hooks, 4, must be sprung into engagement with these loops, 13, by the use of some force, the wire of which the handle is formed having sufficient resiliency to permit this, and when the locking hooks and loops, 4 and 13, are once engaged, the engagement of the guiding portions, 5 and 14, will prevent the locking portions from being accidentally disengaged. The basket can now be handled as conveniently as if the handle were in one piece and rigidly secured to the basket. This form of handle is very cheap to make, and is particularly desirable with a very light type of basket such as is used for small fruits, etc., where the weight of the contents will not be likely to cause the attaching members to pull out of the side members, and the centering loop of device, 2, in the center of the hand engaging portion of the bail member will be found very convenient in supporting the basket in horizontal position while it is being filled. The shoulders, 12, of the attaching members are preferably so constructed as

to engage notches or recesses, indicated at e^3 , in the cover, which in the case of a cover of the type shown in Fig. 1, may extend only through the cleat, e^1 , or also through the longitudinal strip beneath, if preferred, said notches being provided at opposite sides of the cover. This permits the shoulders, 12, to hold the cover against longitudinal movement, and where the shoulder, 12, rests on the longitudinal strip, e , as shown in Fig. 3, it also holds the cover against vertical movement. If the notch, e^3 , were extended through both thicknesses of the cover the result would be the same, as the cover is also held against vertical movement by the locking member, 4, of the adjacent bail arm which hooks into the loop, 13, and rests on the top of the cover.

In Fig. 4, I have shown a slightly modified form of the attaching member in which the parts corresponding with those shown in Fig. 3, are given the same numerals with 100 added. In this construction the vertical part, 106, of the attaching member is provided at its lower end with the portion, 107, to extend through the side of the basket, this part terminating in a clinching point, 108, as shown in full and dotted lines, which is adapted to be bent up or clinched upon the inner side of the basket, or of the inner binding strip. The part, 106, is also provided with a portion, 106^a, formed by shearing it from the body of the wire, to form a second clinching point which extends through the side of the basket and through the upper binding strips, and is provided with an end, 106^b, adapted to be clinched on the inner face of the basket side, or inner binding strip, and is preferably bent downward toward the clinching point, 108, thus holding the attaching member very securely in position. The other portions of the attaching member are identical with those previously described with reference to Fig. 3, except that in this figure the shoulder, 112, is shown as engaging a notch, e^3 , in the cover formed in both the cleat, e^1 , and the slat, e , and thus holding the cover against longitudinal movement, the cover being held against vertical movement by the locking portion of the bail member in the manner previously described.

In Fig. 5, I have shown another modified form of attaching member in which the parts corresponding with those shown in Fig. 3, are given the same reference numerals with the addition of 200. In this case, the part, 206, is provided with the sheared clinching point, 206^a, 206^b, as just previously described, and the lower end of the part, 206, is provided with an extension, 207, to pass through a hole in the side of the basket, and adapted to be bent upward alongside the inner face of the inner binding strip, as indicated at 208, the upper end of this portion, 208, extending above the top of the basket as shown at 209,

and engaging a notch, e^4 , in the cover in this instance in the longitudinal strip, e . The other portions of the device being constructed substantially as shown and described with reference to Fig. 3, except that in this case the shoulder, 212, rests on top of the cleat, e^1 , of the cover and need not extend into a recess therein, as the cover will be held from longitudinal movement by the upper end, 209, of the part, 208.

In Figs. 6 and 7, I have shown another slightly different form of attaching member in which the parts corresponding with those in Fig. 3, are given the same reference numerals with the addition of 300. In this form of the attaching member, the vertical portion, 306, is provided with an extension bent upwardly parallel thereto, as shown at 306^a, so as to form a loop, 306^b. The upper end of the part, 306^a, which lies parallel with the part, 306, on the outside of the basket has a portion, 307, extending over the top edge of the basket, and provided within the basket with a downwardly extending arm, 308, terminating in a point, 309, adapted to be forced through the basket from the inside out and to project into the loop, 306^b, as clearly shown in Figs. 6 and 7. The part, 308, will be formed in the manner indicated in dotted lines in Fig. 6, so as to permit the attaching member to be placed in engagement with the upper edge of the basket, and the part, 308, can then be bent into the form shown in full lines in Fig. 6, by a pair of pliers, or by means of a hammer or other tools forcing the point, 309, through the side of the basket and preferably into the loop, 306^b. As the part, 307, is above the upper edge of the basket, the cover is conveniently provided with a notch, e^3 , in the longitudinal strip, e , only, and the shoulder, 312, is conveniently arranged to merely engage the top of the cover, as the top of the cleat, e^1 , thus holding the cover against longitudinal and vertical movement.

It will be understood that, the form of bail member illustrated in Figs. 1 and 2, can be used with any of the attaching members illustrated in detail in Figs. 3, 4, 5, 6, and 7.

In Fig. 8, I have shown a bail member constructed exactly like the one illustrated in Figs. 1 and 2, except that the hand engaging portion, 101, is provided with a centrally disposed arched portion, 102, forming a notch, 102^a, to engage a hook on a ladder or other support, and prevent the basket from tilting materially while it is being filled. The other portions of the bail member shown in Fig. 8, are identical with the parts shown in Figs. 1 and 2, and are given the same numerals with the addition of 100.

In Fig. 9, I have shown another slight modification of the bail member in which the entire hand engaging portion, 201, is formed in an arch or upward curve, so that when engaged with a hook or other support, it will

tend to engage it at a central point and hold the basket substantially level at all times while it is being filled. The other portions of the bail member shown in Fig. 9, are identical with those shown in Figs. 1 and 2, and are given the same numerals with the addition of 200.

Where the side portions of the basket are of sufficient strength to withstand the weight of the contents, as where the basket is of very small size, or is provided with heavy substantial side veneers, it will be unnecessary to connect the attaching members to the bottom of the basket. I prefer, however, to provide means for directly connecting the attaching members to the bottom of the basket, so as to relieve from strain the veneer sides of the basket, and the nails, or other devices by which they are attached to the bottom, where this is deemed necessary or desirable on account of the weight of the contents of the basket, which will be thus transferred from the handle directly to the bottom, and will prevent the handles from being accidentally detached from the basket, or the bottom of the basket from being detached from the sides, which in either case would probably result in the loss of the contents. This is accomplished preferably by employing anchoring devices consisting of thin flat strips of metal as tin, for example, one of which is provided at each side of the basket, and is secured to the adjacent attaching device near the top of the basket, and to the bottom of the basket, and in some instances the anchoring means may extend from one attaching member around the sides and bottom of the basket to the other attaching member.

In Fig. 10, for example, I have shown the basket provided with an anchoring device illustrated in detail in Fig. 11, which is intended to be applied on each side of the basket. This device consists of a thin narrow strip of metal indicated at 15, adapted to engage the side, B, of the basket, and preferably provided with means for attaching it thereto, preferably in the form of clinching points indicated at 16, 16, punched out of the metal and adapted to be forced through the side of the basket and clinched, as shown in Fig. 10. The strip, 15, is also provided with an angular foot portion indicated at 17, to extend beneath the bottom of the basket, and this portion is also preferably provided with a clinching point, 18, formed in the same manner as the points, 16, and adapted to be driven up into the bottom of the basket. The strip, 15, is also provided near the angular portion, 17, with an aperture, 19, through which a nail, 21, may be driven edgewise into the bottom, A, passing through the side, B, and the bottom binding strip, C, which may be either within or outside of the anchoring strip, 15, as preferred, in making up the basket. The anchoring strip, 15, is also

provided near its upper end with an aperture, 20, or apertures, through which the clinching points of an attaching member of the handle may be passed, as clearly shown in Fig. 10. In this figure, I have shown a slightly modified form of attaching member having the vertical exterior portion, 406, provided with the horizontal portion, 407, extending through the aperture, 20, above referred to, and having the portion, 408, bent up on the inside of the basket, provided with the point, 409, extending through the side of the basket and the upper binding strips, the attaching member being provided also with the locking loop, 413, a downwardly extending retaining shoulder, 412, entering a notch in the cover, and a horizontally disposed retaining shoulder, 412^a, to engage the top of the cover, thus locking the cover against both longitudinal and vertical movement, and the attaching device is provided with the upwardly extending arm, 412^b, terminating in the guiding portion, 414. The bail member is constructed in the same manner as indicated in Figs. 1 and 2, and is provided with the locking member, 404, and guiding member, 405, and operates in the same manner as hereinbefore described.

In Fig. 12, I have illustrated another slight modification, in which the basket is shown provided with an anchoring strip, 115, on each side adapted to be secured to the basket as by clinching points, 116, and constructed exactly like the anchoring strip shown in Fig. 11, except that the portion extending under the bottom of the basket is omitted, and the strip is secured to the basket bottom only by the nail or brad, 121, extending through the lower aperture, 119, in the strip. In Fig. 12, I have shown the same form of handle illustrated in Fig. 1, which need not again be described, and which is referred to by the same numerals used in Fig. 1 with 500 added. It will be understood, that, the horizontal portion, 507, of the attaching member passes through the upper hole, 120, in the anchoring strip. In this construction it will be seen, that the weight of the contents of the basket will be supported entirely by the bottom, A, and the weight transferred by the strip, 115, to the handle.

In Fig. 13, I have illustrated a modified form of the anchoring strip, which in this instance is provided with the side portions, 215, formed integrally with a bottom portion, 217, extending beneath the bottom of the basket, the side portions being connected to the sides of the basket as by clinching points, 216, and the bottom strip being connected also to the bottom of the basket as by clinching points, 218. In this instance, the upper end portions of the side pieces, 215, are carried over the top edges of the binding strips and sides of the basket, as in

5 dicated at 222, and downwardly extending portions, 223, engaging the inner face of the binding strips, the upper portions of the anchoring strips being secured to the binding strips and basket sides by the horizontally disposed portions, 609, of the attaching members of the handle, for example, the side portions of the strip being provided with registering apertures for this purpose, 10 and also with apertures, 620, for the passage of the portions, 607, of the attaching members. The handle shown in Fig. 13 is identical with that shown in Fig. 1, and is given the same numerals with 600 added.

15 In Fig. 14, I have shown another modification of an anchoring device indicated at 315, which is constructed in the same manner as that indicated in Fig. 11, except that the upper end is extended to the top of the 20 basket and provided with the horizontal portion, 322, and downwardly extending portion, 323, so as to embrace the upper binding strips, the anchoring strip being provided with an aperture, 320, and with the registering apertures, 324 and 325, to facilitate the 25 attachment of the attaching members of the handle, not illustrated in this figure. It will be understood, that, the bent over portions of the strip may be secured to the basket in 30 any other desired manner if preferred, or found desirable.

What I claim and desire to secure by Letters Patent is:—

1. In a handle for wooden baskets, the combination with a pair of metallic attaching members adapted to be secured to the basket adjacent to its upper edge only, and provided with guiding and locking portions at different points vertically thereof, a separately 35 formed metallic bail member having a hand engaging portion and downwardly extending arms, each provided with guiding and interlocking portions at different points longitudinally thereof, to interengage with the guiding and locking portion of said attaching members, and anchoring devices for connecting each of said attaching members with the bottom of the basket, to relieve the sides of 40 the basket from the weight of the contents.

50 2. In a handle for wooden baskets, the combination with a pair of metallic attaching members adapted to be secured to the basket on opposite sides adjacent to the upper edge of the basket, a separately formed bail member provided with means for engaging said attaching members and forming therewith the handle of the basket, and anchoring means consisting of flat metal strips for engaging the sides of the basket, and provided 55 with means for connecting them with the attaching members of the handle and with the bottom of the basket.

60 3. In a handle for wooden baskets, the combination with a pair of metallic attaching members adapted to be secured to the basket

on opposite sides adjacent to the upper edge of the basket, a separately formed bail member provided with means for engaging said attaching members and forming therewith the handle of the basket, and anchoring means comprising flat metal strips for engaging the sides of the basket, and provided with portions extending beneath the bottom of the basket, and means for connecting said strips to the basket adjacent its upper edge, 70 said strips being provided at their upper ends with means for engaging the attaching members of the basket.

4. In a handle for wooden baskets, the combination with a pair of metallic attaching members adapted to be secured to the basket adjacent to its upper edge, and provided with guiding and locking portions at different points vertically thereof, a separately formed metallic bail member having a hand engaging portion and downwardly extending arms, 75 each provided with guiding and interlocking portions at different points longitudinally thereof, to interengage with the guiding and locking portion of said attaching members, and anchoring means comprising vertically disposed strip portions of sheet metal, provided with means for attaching them to the sides of the basket and to the bottom thereof, 80 said strips being provided adjacent to their upper ends with apertures to receive the attaching members for connecting them with said attaching members of the handle.

5. An attaching member for handles of wooden baskets comprising an anchor member attached to the side and bottom of the basket, a metallic attaching member having a vertically disposed portion engaging the exterior of the basket and two horizontally disposed portions, one of said horizontally disposed portions extending through the side of the basket adjacent its upper edge and through the anchor member, and the other portion extending through the basket adjacent its upper edge, said portions lying in different vertically spaced planes, said attaching member including a means for attaching a handle bail thereto.

6. In combination, a veneer basket having reinforcing strips adjacent the upper edge thereof, and handle attaching members each comprising a single metallic member having a vertically disposed portion engaging the exterior of the basket, a horizontally disposed portion passing through the basket immediately below said reinforcing strips, a second vertically disposed portion lying inside of said basket, a horizontally disposed portion passing through said basket and said reinforcing strips and lying in a plane separated from the first horizontal portion, a bail, and means for connecting the bail to the first vertically disposed portion.

7. In a handle for wooden baskets, a pair of attaching members each comprising two

vertically disposed parts, one engaging the outside of the basket, and the other engaging the inside of the basket, and horizontal portions connected with said vertical parts and passing through the plane of a side of said basket in different vertically spaced planes adjacent the upper edge of the basket, one of said vertical parts extending above the top of the basket side to engage a notch in the cover to prevent longitudinal movement thereof, and a separately formed bail member arranged for detachable engagement with the attaching members.

8. In a handle for wooden baskets, a pair of attaching members each comprising two vertically disposed parts, one engaging the outside of the basket, and the other engaging the inside of the basket, and horizontal portions connected with said vertical parts and passing through the plane of a side of said basket in different vertically spaced planes adjacent the upper edge of the basket, one of said vertical parts extending above the top of the basket side to engage a notch in the cover to prevent longitudinal movement thereof, and a separately formed metallic bail member having a hand engaging portion and downwardly extending arms, each provided with guiding portions and locking portions at different points vertically thereof, to interengage with the guiding and locking portions of said attaching members.

In testimony whereof I affix my signature.
HENRY W. KRAMER.
